CLAIM

The ornamental design for a flower shaped earphone, as shown.

DESCRIPTION

FIG. 1 is a front perspective view of a flower shaped earphone showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The claimed earphone is flower shaped and is used to listen a desired audio.
